(57) **CLAIM**

The ornamental design for a reservoir for a cleaning device, as shown and described.

DESCRIPTION

FIG. 1 is a front perspective view of a reservoir for an ear cleaning device;

FIG. 2 is a back perspective view of the reservoir illustrated in FIG. 1;

FIG. 3 is a bottom view of the reservoir illustrated in FIG. 1;

FIG. 4 is a top view of the reservoir illustrated in FIG. 1;

FIG. 5 is a right side view of the reservoir illustrated in FIG. 1;

FIG. 6 is a left side view of the reservoir illustrated in FIG. 1;

FIG. 7 is a front view of the reservoir illustrated in FIG. 1; and,

FIG. 8 is a back view of the reservoir illustrated in FIG. 1. The dashed broken lines depict portions of the article and form no part of the claimed design. The dash-dot broken lines depict the bounds of the claimed design and form no part thereof.

1 Claim, 8 Drawing Sheets
